US0D1043975S

(12) **United States Design Patent** (10) Patent No.: **US D1,043,975 S**
(45) Date of Patent: ** Sep. 24, 2024

(54) **FLUID TRANSFER ADAPTER**

(71) Applicant: **Siemens Healthcare Diagnostics Inc.**,
Tarrytown, NY (US)

(72) Inventors: **Janine Cox**, Stoughton, MA (US);
Michael Chen, Sharon, MA (US);
Justin DeSilva, Mendon, MA (US);
Justin Davis, Raleigh, NC (US); **Mark Vaughan**, Foxborough, MA (US)

(73) Assignee: **Siemens Healthcare Diagnostics Inc.**,
Tarrytown, NY (US)

(**) Term: **15 Years**

(21) Appl. No.: **29/869,967**

(22) Filed: **Jan. 13, 2023**

Related U.S. Application Data

(63) Continuation-in-part of application No. PCT/US2022/074580, filed on Aug. 5, 2022, and a continuation-in-part of application No. PCT/US2022/074578, filed on Aug. 5, 2022, and a continuation-in-part of application No. PCT/US2022/074582, filed on Aug. 5, 2022, and a continuation-in-part of application No. PCT/US2022/074577, filed on Aug. 5, 2022.

(57) **CLAIM**

The ornamental design for a fluid transfer adapter, as shown and described.

DESCRIPTION

FIG. 1 is a front perspective view of the fluid transfer adapter.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof; and,

FIG. 7 is a bottom plan view thereof.

The broken lines depict portions of the fluid transfer adapter that form no part of the claimed design; the broken lines and the unshaded surfaces form no part of the claimed design.

1 Claim, 6 Drawing Sheets
